3,355,688 INDUCTOR WITH A REINFORCED PLASTIC FORM

Stanley A. Adams, South Haven, Mich., assignor to
Adams Electronics, Inc., a corporation of Michigan
Filed Jan. 26, 1966, Ser. No. 523,150
8 Claims. (Cl. 336—192)

ABSTRACT OF THE DISCLOSURE

A thermoplastic coil form from which metallic terminal lugs project. Coil leads are soldered to the terminal lugs while assembled on the coil form. The lugs are secured to an end portion of the coil form and a heat resistant insert collar to firmly hold the terminal lugs in place while the coil leads are being soldered.

This invention relates generally to new and useful improvements in electrical components, and more particularly to a plastic coil form having a reinforced collar section.

Coil forms now in use are generally in the form of elongate hollow cylindrical members of paperboard, plastic or the like, having coil windings thereon with the ends of the coil connected by soldering to terminal lugs. These terminal lugs are provided for conveniently connecting the coil form to various other electrical components. A major problem has been encountered, however, when soldering the coil ends to the terminal lugs associated with plastic type coil forms. This problem involves the movement of the terminal lugs from their mounting on the coil form during the soldering of the coil ends thereto inasmuch as the plastic coil forms have a tendency to melt due to the heat of soldering. Accordingly, when plastic coil forms are used, a holding device for the lugs and form has normally been required to prevent such lug movement. This invention provides means for allowing the use of plastic coil forms while eliminating the necessity for such holding devices, as the problem of lug movement has been alleviated.

It is an object of the invention to provide a molded plastic coil form with which there is no problem of lug movement when soldering the coil ends to the terminal lugs.

It is another object of the present invention to provide a plastic coil form which is faster, more efficient and easier to manufacture, and which additionally is less expensive than previous similar coil forms.

It is a further object of the present invention to provide a plastic coil form utilizing a reinforced collar for facilitating the attachment of terminal lugs thereto, as well as preventing the movement of the terminal lugs during the attachment of the coil ends thereto.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is an elevational view of a coil form comprising a first embodiment of the present invention;

FIGURE 2 is an elevational view of a coil form comprising a second embodiment of the present invention;

FIGURE 3 is an enlarged partial vertical sectional view taken through the bottom end of the coil form illustrated in FIGURE 2; and

FIGURE 4 is an enlarged bottom plan view of the coil form illustrated in FIGURE 2.

Referring now more particularly to the drawings, and specifically to FIGURE 1, reference numeral 10 generally denotes the coil form comprising the first embodiment of

2

the present invention. The coil form 10 includes a coil form body 12 of elongate hollow tubular construction and which is preferably of an insulating material such as nylon or other suitable plastic material. The coil form body 12 has mounted thereon in the usual or conventional fashion, a coil winding generally denoted by reference numeral 14. Further, a plurality of lugs generally denoted by reference numeral 16 are mounted at the bottom end of the coil form body 12, and the ends 18 and 20 of the coil winding 14 are attached to first and second of the lugs 16 at the attach area generally denoted by the reference numeral 22. The coil ends 18 and 20 are preferably soldered to the lugs 16 in the attach area 22. It will be appreciated from a description of the second embodiment of the present invention infra, as illustrated in FIGURES 2-4, that the mounting of the lugs 16 on the coil form body 12 is generally similar for the two embodiments, the major difference being in the location of the attach areas 22.

Referring now to FIGURES 2-4, it will be observed that a coil form generally denoted by reference numeral 24 is provided, the coil form being generally similar to the form 10 described above. The coil form 24 includes a coil form body 26 which is identical to the body 12 described above, including enlarged end portion 28 having a thickened wall portion 30. The internal diameter of the enlarged end portion 28 is slightly larger than the internal diameter of the remainder or upper portion of the hollow tubular coil form body 26, and an annular shoulder 32 is thus defined below the thickened wall 30, the shoulder 32 being provided for a purpose to be described more fully below.

A coil winding generally denoted by reference numeral 34 is mounted on the coil form body 26 in the usual manner, the coil winding 34 having the ends 36 and 38 extending downwardly for mounting on first and second of the terminal lugs generally denoted by reference numeral 40. Inasmuch as the coil form body 26 is of a plastic type material which has a tendency to melt or flow upon the application of heat thereto, or is generally thermoplastic, it will be apparent that the heat applied during the soldering of the coil ends 36 and 38 to the terminal lugs 40 will adversely affect the mounting of the terminal lugs on the coil form body 26, causing the lugs to move. However, it should also be apparent that the coil form body 26 will not melt or flow at the normal operating temperatures to which the body is subjected. Thus, in order to alleviate or prevent the foregoing problem, an insert generally denoted by reference numeral 42 is provided, the insert comprising a hollow tubular collar 44 which is of approximately the same outer diameter as the inner diameter of the enlarged end portion 28, having the same wall thickness as the thickness of the shoulder 32. Thus, the collar 44 is adapted to fit snugly within the enlarged end portion 28 and against the shoulder 32, the shoulder, of course, limiting the distance which the collar can be mounted into the body 26. The collar 44 is preferably a phenolic impregnated fibrous material such as paper or the like, which is preferably thermo-setting so as not to be affected adversely by the soldering heat.

Referring specifically now to FIGURE 3, it will be observed that the terminal lugs 40 include the bottom portion 46 which extends downwardly past the end of the coil form body 26 and which, of course, allow the coil form to be easily mounted on a printed circuit board or the like. The terminal lugs 40 further include a body portion 48 having struck out legs 50 and 52 thereon for enabling the lugs 40 to be mounted on the coil form body 26. Thus, it will be appreciated that during the fabrication of the coil form 24, the collar 44 is first inserted into the enlarged end 28 and against the shoulder 32, and at this time the lugs 40 are inserted into the molded form and

through the collar 44, being clinched through aligned apertures in the body 26 as illustrated best in FIGURES 3 and 4.

It will be observed in FIGURES 2-4 that the terminal lugs 40 each include an outstanding upper end or head portion 54 to which the coil ends 36 and 38 are normally mounted and soldered, as indicated by the numeral 56, corresponding to the attach area 22 as described in reference to the embodiment of the invention illustrated in FIGURE 1. Thus, after the lugs 40 have been mounted as described above, the coil ends 36 and 38 will be soldered to the head 54 of first and second of the lugs, and although the application of heat during the soldering makes it likely that the plastic coil form body 26 will begin to melt, the phenolic impregnated collar will not be affected by this heat and thus the terminal lugs 40 will be maintained in place and movement thereof will be eliminated. Of course, it will be appreciated that the embodiment of the invention illustrated in FIGURE 1 is quite similar in construction to that illustrated in FIGURES 2-4, the lugs 16 not having the head portion 54 thereon to which the coil ends are attached, but the lugs otherwise being substantially identical. Thus, the lug holding devices formerly necessitated when soldering the coil ends to the lugs are no longer needed to prevent lug movement due to the use of the collar inserts provided by the instant invention.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. In combination, a tubular body member of thermoplastic insulative material having a thermal flow temperature lower than soldering temperature, a plurality of lugs mounted on said body member, an electrically conductive device mounted on said body member having leads soldered to said lugs, and thermo-setting holding means mounted in said body member for preventing movement of said lugs relative to the electrically conductive device.

2. The combination of claim 1 wherein said body member includes an enlarged lower end and a shoulder provided in said lower end, said thermo-setting holding

means comprising a collar in said enlarged lower end abutting the shoulder.

3. The combination of claim 2 wherein said electrically conductive device is a coil winding and said tubular body member is an elongate plastic coil form having one end from which said lugs depend, said lugs including means thereon for clinching said lugs to said enlarged end portion of said body member, said clinching means extending through said collar as well as said body member, whereby movement of said lugs will be prevented during application of soldering heat.

4. The combination of claim 1 wherein said thermo-setting holding means comprises an insert element received internally within the tubular body member and fastening means extending through the body member for securing the lugs to the insert element.

5. The combination of claim 4 wherein said tubular body includes a diametrically enlarged end portion within which the insert element is received and from which the lugs project.

6. The combination of claim 5 wherein said fastening means includes legs struck out from the lugs extending through aligned apertures in the body member and the insert element.

7. The combination of claim 4 wherein said fastening means includes legs struck out from the lugs extending through aligned apertures in the body member and the insert element.

8. A coil form comprising, a generally cylindrical hollow body member of a generally thermo-plastic material, a coil winding mounted on said body member, a collar received in one end of said body member, said collar being of generally thermo-setting material, and a plurality of lugs mounted on said body member at said one end, said lugs including means extending through generally aligned apertures in said body member and said collar whereby said collar will be retained within said body member and said lugs will be fixedly mounted on said body member.
